UNITED STATES PATENT OFFICE.

CHARLES L. DAVIDSON, OF NEW YORK, N. Y.

SOOT-BLOWER APPARATUS FOR STEAM BOILERS.

Application filed June 25, 1921. Serial No. 480,309.

This invention relates to soot blower apparatus for steam boilers.

The object of the invention is to provide apparatus which is simple in structure, economical to construct, install and maintain, and efficient in operation, for blowing or removing the soot and other deposits which accumulate upon the tubes of steam boilers.

A further object is to provide an efficient soot blower apparatus wherein removal of boiler tubes to accommodate the installation of the blower apparatus is avoided.

A further object is to provide a blower apparatus of the nature referred to wherein individual elements of the blower system, when not in use, are withdrawn from position for use, into retracted position where protection is afforded therefor from the heat of the boiler furnace.

A further object of the invention is to provide means whereby individual blower elements are normally maintained in an initial position such as to prevent drippings from the blower perforations or nozzles falling upon the boiler tubes when the blower elements are not being used to perform their blower functions.

Other objects of the invention will appear more fully hereinafter.

The invention consists substantially in the construction, combination, location and relative arrangement of parts, all as will be more fully hereinafter set forth as illustrated in the accompanying drawings and finally pointed out in the appended claim.

In the drawings,—

Fig. 1 is a view in rear end elevation of a tubular steam boiler, illustrating the application thereto of a soot blower apparatus embodying the principles of my invention;

Fig. 2 is a central vertical longitudinal section of the same.

Fig. 3 is a broken detail view in section illustrating a ball jointed operating connection to a blower element.

Fig. 4 is a view similar to Fig. 3 illustrating an actuating arrangement for an element of the blower apparatus.

Fig. 5 is a view in end elevation of the construction shown in Fig. 4.

Fig. 6 is a section on the line 6, 6, Fig. 4.

Fig. 7 is a fragmentary detail view in section illustrating an arrangement wherein a transversely disposed blower element is withdrawn into position to be protected from

the heat of the boiler when not required for use.

Fig. 8 is a view similar to Fig. 7, illustrating an arrangement wherein a longitudinally disposed blower element is withdrawn from working position when not required for use and protected from the boiler heat.

Fig. 9 is a view in front elevation showing a modified arrangement for rotating a blower element.

Fig. 10 is a view in side elevation of the same.

Fig. 11 is a view in section on the line 11, 11, Fig. 10.

Fig. 12 is a similar view on the line 12, 12, Fig. 10.

The same part is designated by the same reference numeral wherever it occurs throughout the several views.

It is among the special purposes of my present invention to provide a soot blower apparatus which avoids many practical objections in the installation and operation of apparatus of this nature. I also propose to avoid the necessity of removing any of the tubes of the boiler to permit installation of the blower system. I also propose to locate elements of the blower system so as to effectively clean or remove soot from the boiler tubes in the lower part of the boiler where the heat is greatest, and to provide means for protecting the blower elements located in this region from the furnace heat when said elements are not in use.

In the accompanying drawings I have shown an illustrative form of soot blower apparatus embodying the principles of my invention as applied to a steam boiler of the well known B. & W. tubular type. It is to be understood, however, that my invention is not to be limited or restricted in respect to its application to any particular make or type of boiler.

Referring to the drawings, 10 designates the tubes of a tubular boiler, 11 the steam drums, and 12 the end walls, 13 the side walls and 14 the bridge wall, and 15, a super-heater. As above pointed out, these features may be of the usual or any desired type or make. Extending through the shell or casing walls are the soot blower pipes 16, 17, 18, to which steam is delivered from the drums 11, or from the super-heater 15, as may be desired, through pipes 19, controlled by valves 20. Any desired number of these

blower pipes may be employed, and they may be arranged in various relations with respect to the steam generating elements, or tubes of the boiler. In the arrangement 6 shown as an illustrative embodiment of my invention, but to which, of course, my invention is not to be limited or restricted, two blower elements 16 are employed, and these are disposed above and in parallel 10 relation to the boiler tubes 10, and, in the type of boiler shown, preferably, in a downwardly inclined position from the front to the rear of the boiler, the lower ends of said elements extending through the rear wall 12 of the boiler setting or casing, where they are suitably connected to the steam supply 15 pipes 19.

The blower pipe or element 17, is shown located below the front end of the boiler 20 tubes, and extends transversely across the boiler. This element, although located in close proximity to the furnace chamber, is protected, when not in use in the performance 25 of its blower functions, by being retracted behind a protecting bridge or ledge 21.

The blower pipe or element 18 is shown in Figs. 1 and 2, as extending transversely across the boiler at a point beneath the boiler 30 tubes adjacent the rear ends thereof. In this case, however, the said pipe is protected from the furnace heat by the furnace bridge wall 14, which is interposed between said pipe and the furnace chamber.

If desired, and as indicated in Figs. 1 and 8, blower pipes or elements 22, located below the boiler tubes, may also be employed and arranged to extend in parallel relation 40 to the tubes. In this case the elements 22 will be mounted in downwardly inclined position from the front end of the boiler towards the rear end, as in the case of elements 16. The elements 22, are mounted adjacent the sides of the boiler casing and 45 in such manner that they may be moved into a retracted position behind a ledge or wall 21, when not required for use in effecting a cleaning of the tubes, so as to be protected from the effects of the heat of the boiler 50 furnace.

The downward inclination of the blower pipes or elements 16 from the front towards the rear of the boiler permits any leakage 55 of steam into the blower system due to leaky valves, to drain from the boiler to a point where drippings will fall clear of the boiler tubes, thereby avoiding the danger of corroding or puncturing the boiler tubes, and of explosions therein. This danger is 60 avoided, of course, in the case of elements 17, 18 and 22 by reason of their location below the boiler tubes.

The various pipes or elements of the blower system are perforated along their 65 lengths, and, preferably, these are in the

form of nipples, as indicated at 24, so that when steam is supplied to the elements, it is delivered therefrom in jets as indicated in Fig. 7.

In the work of effectively removing the 70 soot, or other deposits, from the boiler tubes, and in order to reach and clean a maximum number of the tubes, the blower elements, or certain ones of them are preferably mounted for axial rotative movement, whereby the steam jets therefrom may be directed through a wide range of application. For example, I have shown the blower 75 elements 16 mounted for axial rotative movement, which movement is imparted thereto in any suitable manner, as, for instance, a hand wheel 25, having suitable connection with the end of the element which extends through the rear wall 12 of the boiler casing.

In order to permit such axial rotative movements of the elements of the blower, notwithstanding deflections or bends in the elements caused by the heat to which said elements are subjected, I prefer to employ a ball or other form of flexible joint connection between the ends of the blower elements and the pipes 19 which deliver the steam thereto. An illustrative form of ball joint connection is shown in detail in Fig. 3, wherein the end of the blower element 95 which extends through the rear wall of the boiler casing receives one end of a sleeve 26, within the other end of which is received the ball portion 27 of a sleeve 28, which is connected to the steam supply pipe 19. A 100 suitable packing indicated at 29, preferably a soft metal packing, is interposed between the ball 27 and its seat in the sleeve 26. The operating member 25 for imparting rotative movement to the blower element 16, may be 105 conveniently mounted upon the sleeve 26. The end of the blower element extends through a flanged sleeve 30, mounted in the casing wall 12, and has mounted thereon a collared flange 31. A lip or projection 32 110 on this flange cooperates with a pin or stop 33 on the bearing sleeve 30 to determine the limit of rotative movement which may be imparted to the blower element.

The blower elements or certain of them, as 115 above indicated, are mounted so as to be movable into and out of position for use, and when retracted out of position for use may be protected from the heat of the furnace by means of an intervening ledge or bridge. To permit such movements I provide 120 said elements with angle portions at their ends, which angle portions form pintles or journals upon which said elements are rocked. I have shown such an arrangement 125 in Figs. 1, 4, 7, and 8, wherein the angle or crank ends 34, of blower elements 17, 22, are shown extended through a flanged bearing sleeve 35 mounted in the casing wall 13, and are connected to operating elements, 130

shown in this instance as hand wheels 36, similar in purpose and function to the wheel 25 above described with reference to the blower element 16. In like manner a ball joint connection, indicated at 37, similar in all respects to the ball joint connection above described, forms a connection between the blower element 17 and its steam supply pipe 19. In this arrangement by means of the operating element 36, the crank arm end portions 34, of the blower element are axially rotated so as to cause the intermediate portion of said element to be raised or moved into position for accomplishing its blower function, as indicated in full lines in Fig. 7, or shifted into retracted position behind a protecting ledge or bridge 21, as indicated in dotted lines in the same figure, when not required for use.

20 In the structure so far described, the blower elements are rotated by means of hand or other wheels indicated at 25, 36. In practice the blower elements required to be rotatively actuated are sometimes located at 25 such a height as to make it inconvenient or difficult to reach. In such case the rotative movement of said elements may be effected in various other ways. It is preferable that the actuation of the blower elements, when required, be effected smoothly and evenly. In Figs. 9, 10, 11 and 12 I have shown a simple arrangement for this purpose wherein a worm gear 50 is mounted on or connected to the blower element to be 30 rotated, and is engaged by a worm 51, carried by a shaft 52, journaled in brackets 53, fastened to the boiler casing 12 or to the sleeve 30 through which the blower element extends. To the shaft 52 is connected an 40 operating rod and handle 54 by which the worm 51 may be rotated, and this operating rod and handle may be led to any convenient point.

It is desirable that the blower elements be normally maintained in a certain or given initial position. This may be accomplished in many different ways. A simple and efficient arrangement is shown wherein a coil spring 38 is mounted on the blower element, one end of said spring being connected to the journal sleeve in the casing wall through which the end of blower element extends. The other end of said spring is connected to the blower element. The tension of this 55 spring is normally exerted upon the blower element to maintain the lip or projection 32 on collar 31, in bearing contact against the stop 33, and hence maintain the blower element in a given initial position. This initial position should be such that any leakage of steam into the blower element through faulty valves will not cause dripping or continuous impact of steam jets upon a particular tube, or spot on a tube, of the boiler.

65 In order to take care of any accumulation

of condensation within the blower elements, I provide said elements with drain pipe connections indicated at 39, in which are located valves 40, one of which is diagrammatically included in Fig. 4.

The drain connections 39, if desired, may deliver into the boiler casing at a convenient point where the drippings or drainings therefrom will cause no injurious action upon the boiler tubes, or other portions of the boilers.

70 In some cases it may be desirable to cool the blower elements when not in use for blower purposes, and it is also desirable to be able to ascertain whether or not any leakage of steam occurs in the blower system. I have provided a simple arrangement for accomplishing these purposes wherein I employ a funnel member or elbow 60 in the drain connection 39, (see Fig. 3) so constructed and arranged as to provide an air 80 intake opening around the drain connection. For example, one section of the drain pipe connection may pass loosely into one end of the funnel elbow. In this manner when the blower is not in use for blower purposes air 90 may be taken into the blower system through this air space afforded by the elbow funnel, thereby tending to keep the blower elements cool. At the same time, in case of any steam leakage in the blower system, the fact will 95 be disclosed by a slight escape of the steam at the elbow funnel connections.

From the foregoing description it will be seen that I provide an exceedingly simple 100 steam blower system which is inexpensive to install and maintain, and easy to operate, and wherein removal of boiler tubes is not necessary in making the installation of the system. It will also be seen that I provide against the danger of interruption of the 105 operation of the blower system through warping or bending of the elements thereof, or injury to or danger from rupture or explosion of the boiler tubes due to faulty action of the blower system or of its elements. It 110 will also be seen that I reduce the external piping required for the blower system to a minimum thereby leaving comparatively free and unobstructed the alleyways usually provided between adjacent boilers in a bank. I also am enabled to apply the action of the blower elements to the lower sides of the tubes of the boiler in the region of the lower part of the boiler and where cleaning of the tubes is most important, without unduly 115 subjecting the blower elements when not in use to high heats of the furnace.

120 It will be understood that many variations and changes in details of structure and arrangement of parts will readily occur to persons skilled in the art without departure from the spirit and broad scope of my invention, as defined in the claim. I do not desire, therefore, to be limited or restricted to the 125 specific details and arrangements selected 130

and shown as illustrative of the principles involved.

But what I claim as new and useful and of my own invention, and desire to secure by Letters Patent is,—

The combination with a steam boiler having a casing, of an oscillatable perforated blower element permanently mounted within the casing, a protecting wall within said casing behind which said element normally rests to protect it from direct heat, means

on the outside of the casing for moving said blower element out of normal position for use and means for maintaining said blower element in protected position against which ¹⁵ the first mentioned means acts in moving said blower element into position for use.

In testimony whereof I have hereunto set my hand on this 18th day of June A. D., 1921.

CHARLES L. DAVIDSON.
